UNITED STATES PATENT OFFICE

WILLIAM C. LAMKINS, OF NEWPORT, ARKANSAS

END GATE

Application filed April 23, 1929. Serial No. 357,575.

The present invention relates to an end gate for wagon bodies and the like and has for its prime object to provide a means for holding the end gate tightly on the end of the body.

5 Another very important object of the invention resides in the provision of an apparatus of this nature which is exceedingly simple in its construction, strong and durable, inexpensive to manufacture, easy to manipulate, thoroughly efficient and reliable in use and otherwise well adapted for the purpose for which it is designed.

With the above and numerous other objects in view, as will appear as the description proceeds, the invention resides in certain novel features of construction and in the combination and arrangement of parts as will be hereinafter more fully described and claimed.

In the drawings:

20 Figure 1 is a top plan view of the rear end of a wagon body showing my invention associated therewith.

Figure 2 is a side elevation thereof.

25 Figure 3 is a perspective view of one of the wear plates.

Figure 4 is a rear end elevation, showing one corner only.

30 Figure 5 is a fragmentary perspective view of the end gate.

Figure 6 is a vertical section taken on the line 6—6 of Figure 1.

Figure 7 is a perspective view of one of the reinforcing plates.

35 Figure 8 is a perspective view of one of the bolts.

Referring to the drawings in detail, it will be seen that the numeral 5 denotes the sides of the wagon body and the numeral 6 the end gate, which is provided adjacent its ends 40 with a pair of spaced vertical cleats 7 to straddle the ends of the sides 5 and notches 8 are provided in the upper edges of the tail gate to register with the spaces between the cleats 7. Indentures 9 are provided in the rear face of the tail gate. Wear plates 10 are

disposed diagonally across portions of the rear face of the end gate being fastened in place by suitable screws 11 and having openings 12 registering with the indentures 9. Reinforcement longitudinally extending elongated plates 14 are fastened at their forward ends as at 15, inside the sides 5, and at their rear ends by means of bolts 16. The heads are disposed inwardly and the threaded ends are disposed outwardly. Levers 17 have 50 their forward ends pivoted on the bolts 16 and tightening nuts 18 are threaded on the bolts to hold the levers in place and are provided with handles 19. The levers are adapted to rock down and extend through the notches 8 and at their rear ends have lateral depending extensions 20 through which are threaded set screws 21 having reduced ends 22, for extending through openings 12 and into indentures 9. Thus it will be seen that the tail gate may 55 be securely clamped against the rear end of the body in a closed position or in a partially closed position, and by releasing the set screws, the levers may be swung up out of the way and the tail gate easily removed. 60

It is thought that the construction, operation, utility and advantages of this invention will now be quite apparent to those skilled in this art, without a more detailed description thereof. The present embodiment of the invention has been disclosed in detail, merely for the purpose of exemplification, since in actual practice it attains the features of advantage enumerated as desirable in the statement of the invention and the above description. 75 It will be apparent that changes in the details of construction and in the combination and arrangement of parts may be resorted to, without departing from the spirit or scope of the invention as hereinafter 80 claimed or sacrificing any of its advantages. 85

Having thus described the invention, what I claim as new is:

In combination, a wagon body including a pair of sides, an end gate having two pairs 90

of cleats vertically disposed on the ends thereof in spaced relation to receive the ends of the sides, said gate having notches registering with the spaces between the cleats and formed in the upper edge of the end gate, levers pivotally mounted on the sides and adapted to be swung in a vertical plane into the notches and between the cleats, extensions depending from the rear ends of the levers, and means carried by the extensions for engagement with the end gate for clamping the same against the sides and for retaining the levers in the slots.

In testimony whereof I affix my signature.

15 WILLIAM C. LAMKINS.
